UNITED STATES PATENT OFFICE.

EDWARD NICHOLAS, OF KOKOMO, INDIANA.

AUTO BLOCK-SIGNAL.

1,345,218.

Specification of Letters Patent. Patented June 29, 1920.

Application filed June 12, 1919. Serial No. 303,572.

To all whom it may concern:

Be it known that I, EDWARD NICHOLAS, a citizen of the United States, residing at Kokomo, in the county of Howard and State of Indiana, have invented certain new and useful Improvements in Auto Block-Signals; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in auto block signals adapted to be attached to an automobile and affording means whereby semaphores having signs thereon, indicating the movements of the car as to whether or not the same is to turn to the left or right, stop, back or go ahead, and consists of a simple device of this character which may be applied to various makes of cars.

The invention consists of a device of this character which may be clamped to the body of a car and provided with push buttons within the car for the convenience of the operator who may cause the signals to be displayed while within a closed car and without the necessity of the operator using his arm to make the signal.

I illustrate my invention in the accompanying drawings which, with the letters of reference marked thereon, form a part of this application, and in which:

Figure 1 is a front elevation, Fig. 2 is a side elevation, Fig. 3 is a detail in elevation of a selector plate, Fig. 4 is an enlarged view in elevation partly in section, and Figs. 5 and 6 are detail views.

Reference now being had to the details of the drawings by numerals:

1 designates the casing of the device which is made of any suitable material and is provided with a clamp-screw 2 secured to the bracket member 3 so arranged that the device may be secured to the side of a car. Said casing has a shaft 4 mounted in the opposite walls thereof and upon which the disks 5 are pivotally mounted, each disk having secured thereto a semaphore 6 having indicating letters thereon, one designating that when the signal is

displayed the car is to turn to the right, another indicating that the car is to turn to the left, another that the car is to stop, another that it is to back up and the fifth that the car is to go straight ahead. While 60 I have illustrated five of these semaphores, it is obvious that I do not confine myself to any certain number. Each disk has an integral weighted portion 7 notched as at 8 and the several notches are adapted to 65 register when the semaphores are in their normal closed positions. It will be understood that the weighted portion of each semaphore when released will cause the latter to be thrown to a horizontal position, 70 its upper limit being regulated by the bail-shaped member 13 fastened to the casing, and which has a yielding movement tending to gradually stop the semaphore when it reaches its horizontal position. 75

A series of levers 14 are pivotally mounted upon a pin 15 (see Fig. 4) and springs 16, secured to the top of the casing, bear one against each lever tending to hold the same frictionally against the convexed edge 80 18 of a weighted portion of the disk, and provided for the purpose of holding the semaphore normally in a closed position within the casing. One of the paddles, adapted to bear the word "Stop" has a 85 handle 19 secured thereto and which forms means for returning the same individually to its starting position whereas the other handle 19' may be utilized for returning any one or all of the semaphores to their 90 normal positions.

Secured to the two levers 14 and the push buttons 20 each having a stem extending through an aperture in the top and each push button bearing the indication upon the 95 particular paddle to which it is attached.

A buffer member 21 is fastened in the casing between the side walls and against which the edge of the weighted portion of the disk carrying a semaphore is adapted 100 to contact in order to prevent jar when the weight reaches its lowest limit.

In order to illuminate the signals, electric lamps 22 are mounted upon the opposite sides of the casing and which may be connected with batteries, and also provided with switch means for throwing same on or off, but which form no part of the present invention.

In operation, the device is preferably ap- 110

plied to the side of the car adjacent to the operator, usually upon the left side and clamped to the body of the car.

- When it is desired to indicate as to whether or not the car is to turn to the right, left, stop, back up or go ahead, the operator will depress a certain push button which will cause the semaphore desired to be displayed to be released and the weighted portion of the semaphore will cause the latter to be thrown to a horizontal displaying position. When it is desired to return the semaphore to its normal position, it may be done by the operator merely raising the handle, throwing the paddle to its normal position and the spring frictionally engaging the convexed end of the weighted portion will normally hold the paddle within the casing.
- 20 One of the paddles, as will be noted, has a distinct and separate handle and which is upon the one adapted to bear the word "Stop", and which may be returned to its normal position, after having been displayed, independent of the other lever, which latter may be employed for returning any one or all of the other semaphores to their normal positions.
- By the provision of an apparatus embodying the features of my invention, it will be noted that an auto block safety signal means is provided whereby one or all of the signals may be operated and at night illuminated by the lights, and while I have shown an apparatus as operated manually, it will be understood that either electrical or other mechanical means may be utilized without in any way departing from the spirit of the invention.
- 40 It will be understood that the device may be fastened upon the car in any other way, as to the wind shield or to the door if desired.
- What I claim to be new is:
- 45 1. An automatic block signal for automobiles to designate the movement of a car, consisting of a casing, a series of semaphores pivotally mounted therein and bearing indicating words thereon, a weighted member connected to each semaphore, and means for releasing the weighted member to permit the weighted portion to throw the semaphore to a displayed position, and a lever pivoted within the casing and adapted

to normally return the semaphores within 55 the casing.

2. An automatic block signal for automobiles to designate the movement of a car, 60 consisting of a casing, a series of semaphores pivotally mounted therein and bearing indicating words thereon, a weighted member connected to each semaphore, and means for releasing the weighted member to permit the weighted portion to throw the semaphore to a displayed position, a member pivoted 65 within the casing and having a laterally extending arm adapted to engage the weighted portions of the semaphores, and a lever secured to said arm affording means whereby as the lever is raised said arm is adapted to 70 contact with the weighted portions of the semaphores and tilt the same back within the casing.

3. An automatic block signal for automobiles to designate the movement of a car, 75 consisting of a casing, a series of semaphores pivotally mounted therein and bearing indicating words thereon, a weighted member connected to each semaphore, a series of push buttons, pivotal levers actuated by said push buttons, and springs for holding the levers in frictional contact with said weighted portions, the latter when released adapted to throw the semaphores to displaying positions, and means for returning 80 the semaphores to their normal positions.

4. An automatic block signal for automobiles to designate the movement of a car, 85 consisting of a casing, a series of semaphores pivotally mounted therein and bearing indicating words thereon, a weighted member connected to each semaphore, a series of push buttons, pivotal levers actuated by said push buttons, and springs for holding the levers in frictional contact with said 90 weighted portions, the latter when released adapted to throw the semaphores to displaying positions, each of said weighted portions having a recess formed in the edge thereof, a vertical member mounted within 100 the casing and having a laterally extending arm adapted to engage said recesses, a handle secured to each arm and projecting through the slot in the casing.

In testimony whereof I hereunto affix my 105 signature.

EDWARD NICHOLAS.
